Primary Examiner—Alan P. Douglas**Assistant Examiner**—M. N. Pandozzi**Attorney, Agent, or Firm**—John A. Doninger[57] **CLAIM**

The ornamental design for a drinking tumbler, as shown and described.

DESCRIPTION

FIG. 1 is a top perspective view of a drinking tumbler, showing our new design;
FIG. 2 is a top plan view thereof;
FIG. 3 is a typical elevational view thereof;
FIG. 4 is a bottom view thereof; and,
FIG. 5 is an enlarged cross-section thereof on line 5—5 in FIG. 1.

FIG. 1

FIG. 5

*FIG. 2**FIG. 3**FIG. 4*
